United States Patent Office.

WILLIAM JOHNSON, OF LAMBERTVILLE, NEW JERSEY.

Letters Patent No. 93,998, dated August 24, 1869.

IMPROVED BOLT-THREADING MACHINE.

The Schedule referred to in these Letters Patent and making part of the same.

To all whom, it may concern:

Be it known that I, WILLIAM JOHNSON, of the town of Lambertville, in the county of Hunterdon, and State of New Jersey, have invented a new and useful Machine for Threading Bolts; and I do hereby declare that the following is a full, clear, and exact description of the construction and operation of the same, reference being had to the annexed drawings, making a part of this specification.

My invention relates to revolving die-machines; and consists briefly in the use of friction-bands applied to the periphery of toothed rims in contact with pinion-wheels, working upon screws to open and close the dies, while the machine is kept constantly in motion, thereby obviating the necessity for reversing or stopping the machine.

Also, in the arrangement of stops to regulate the size to be cut, and in the use of die-blocks to facilitate the changing and recutting of the dies.

In the accompanying drawings—

Figure 1 is a front view, having a portion of the die broken out, showing the internal parts of die.

Figure 2 is a vertical cross-section of the same.

Figure 3 represents the face-plate and stops.

Figure 4 shows the arrangement of toothed rims and pinions.

Figure 5 shows the method of attaching die-blocks to screws.

Figure 6 is an end view of the rock-shaft and its connection with the friction-bands.

The several letters in all the figures refer to the same parts.

A is the supporting-frame or principal casting of bolt-cutter.

B is the revolving mandrel and face-plate.

E is the main die-casting, in which the die-blocks are inserted.

G G are the toothed rims, fitted to revolve upon the main die-casting.

L L, the friction-bands.

D D D are the thread-cutting dies.

O O O, movable die-blocks.

S S S, screws, by which the dies are opened and closed.

W W W, pinion-wheels, tapped to fit screws S S S.

N, plate, to hold dies in place.

H, handle or lever.

I, rock-shaft, to operate friction-bands.

P, adjustable stop, to regulate size of bolt.

T, stop on toothed rim, shown by dotted lines, fig. 3.

X, permanent stop in face-plate.

J J, pins, connecting friction-bands to rock-shaft.

F, band, surrounding main die-casting, against which the pinion-wheels press.

R, pulley, by which motion is communicated.

The main die-casting is solidly attached to the face-plate of the mandrel, having slots or openings in which the die-blocks are fitted to slide.

Between the main die-casting and the face-plate, a toothed rim, with a flange on one side, is fitted to revolve freely; and upon the front part of the main die-casting, another toothed rim is fitted in like manner.

Between these toothed rims, at three several points opposite the die-blocks, are placed pinion-wheels, in contact with the toothed rims. Said pinion-wheels have screw-threads cut through them to fit the screws upon which they revolve, and are held in place by a band surrounding the main die-casting, having holes through which one end of the screws slide, while the other end of the screws is fast to the die-blocks.

The flanges of the toothed rims meet together at the centre of the die and form a continuous smooth surface, around which passes the friction-bands, one end of each of said friction-bands being fast to the principal frame or casting, while the other ends are connected to the rock-shaft.

The front toothed rim and the dies are held in place by a plate fastened with screws to the main die-casting.

The face-plate of the mandrel has a groove, in which are the stops to regulate the motion of the dies in opening and closing. One of said stops is solidly attached to the toothed rim next to face-plate.

Another stop is inserted in the groove of the face-plate, said stop being held in place and adjustable therein by means of screws passing through slots in the face-plate.

A permanent stop is also placed in the groove of the face-plate.

A shaft passes through the principal frame-casting at a right angle with the axis of the mandrel of the machine, having a handle or lever attached to one end, and in the face of the other end, (which is enlarged for that purpose,) two pins are inserted, to which the friction-bands are attached.

The mandrel, to which the die is fastened, extends through the principal frame-casting, and is driven by means of a pulley or suitable gearing.

In the accompanying drawings, three cutting-dies only are shown, that being a desirable number; but I do not confine my claim to this number, as any other desired number may be used.

Its operation is as follows:

The machine being in motion, with the dies closed, the lever or handle moved one way, from an upright position, will close one of the friction-bands upon the periphery of one of the toothed rims, holding it at rest a moment, while the die, still in motion, carrying with it the pinion-wheels, causes them to revolve against the toothed rim at rest, and upon the screws, said

screws being held from turning by the die-blocks, to which they are attached, and the pinion-wheels being held in place by the main die-casting and pressure-band, causes the screws, by reason of the thread in the pinion-wheels, to move outward and open the dies, in like manner pressing the handle in the opposite direction will close the other friction-band upon the periphery of the other toothed rim, and the dies are again closed ready for use.

When the die is either opened or closed, which is known by the striking of the stops, the handle or lever is brought to an upright position, and the whole die moves around as left by the friction-bands.

What I claim as my invention, and desire to secure by Letters Patent, is—

1. The main die-casting E, toothed rims G G, pinion-wheels W W W, screws S S S, die-blocks O O O, cutting-dies D D D, stops P T X, pressure-band F, and plate N, combined and arranged as described, and for the purpose specified.

2. The arrangement of the friction-bands L L, rock-shaft I and lever H, or their equivalents, arranged and combined in the manner and for the purpose substantially as described and set forth.

WM. JOHNSON.
